J. W. SOUTHERN,
OVEN TEMPERATURE REGULATOR,
APPLICATION FILED NOV. 30, 1917.

1,273,196.

Patented July 23, 1918.

UNITED STATES PATENT OFFICE.

JOHN WM. SOUTHERN, OF VANCOUVER, BRITISH COLUMBIA, CANADA.

OVEN-TEMPERATURE REGULATOR.

1,273,196.

Specification of Letters Patent. Patented July 23, 1918.

Application filed November 30, 1917. Serial No. 204,657.

To all whom it may concern:

Be it known that I, JOHN W. SOUTHERN, a citizen of the Dominion of Canada, residing at Vancouver, in the Province of British Columbia, Canada, have invented certain new and useful Improvements in Oven-Temperature Regulators, of which the following is a specification.

This invention relates to an oven temperature regulator and time alarm coöperative therewith, the object of which is to prevent the temperature of an oven exceeding certain predetermined limits, whether "medium," "hot" or "very hot," and for sounding an alarm at any desired number of minutes after that predetermined temperature has been attained.

The invention is particularly described in the following specification, reference being made to the drawings by which it is accompanied, in which:

Figure 1 is a front elevation and part section of the heat regulator and alarm.

Fig. 2 is a section of the same on the line 2—2 in Fig. 1.

Fig. 3 is a section on the line 3—3 in Fig. 1.

Fig. 4 is a face view looking in the direction of the arrow 4 in Fig. 1.

30 Removably secured by a bayonet catch 17 on a ring 2 such as is at present used to support an oven thermometer is a chamber 3 of relatively larger diameter and having a dial plate 4 to the underside of which is secured a thermometer 5 with its indicating pointer 6 on the outer face of the dial.

Separated by a partition 8 from that part of the chamber 3 which contains the thermometer is a compartment 7, which is open 40 to the atmosphere through an aperture 9 closable with a slideable shutter 10. A duct 11 directly connects the space within the oven with that end of the compartment 7 in which is the closable aperture 9. The 45 oven end of this duct has a perforated screen across it and the outer end where it delivers into the compartment 7 is closable with a hinged valve 13 which is normally held closed by a light spring 12. This valve 13 50 provides for escape of hot air from the

oven when the temperature is exceeded for which the device is set.

Control of the escape valve 13 is exercised by the indicating pointer 6 of the thermometer in the following manner. Severally 55 pivoted at 15 on the inner wall or partition 8 of the chamber 7 at angular distances apart, is a series of light levers 14. The outer end of each lever 14 projects through an aperture 18 in the wall of the cylinder 60 3, which aperture is elongated in the plane of the movement of the lever. Each lever is formed with a portion 16 to project a short distance through an elongated aperture in the dial plate 4. This projecting 65 end 16 is normally clear of the heat indicating pointer 6 but may be projected, when desired, into the path of the pointer, to be engaged and moved by it. Each lever 14 is flexibly connected intermediate of its ends 70 to the free end of the escape valve 13.

The levers 14 are set at angular distances apart around the dial plate at positions corresponding to thermometer indications representing a "medium," a "hot," or a "very hot" oven and one or the other is brought into the engaging position, that is, its end 16 is projected outward through the dial plate according as one of these heats is required to be maintained in the oven. 75 80

With this arrangement one of the levers 14 according to the temperature required, is drawn forward to project its end 16 through the dial plate 4 and into the path of the thermal pointer 6. When the desired temperature is attained in the oven, the pointer 6 indicating that temperature will engage the projection 16 of the lever 14 which has been drawn out and will move it to open the valve 13. The hot air from the oven 85 is then free to escape through the duct 11 and through the closable aperture 9.

If this escape of hot air lowers the temperature of the oven below what is required and for which the lever has been set, that 90 fall of temperature will cause the thermometer pointer 6 to recede from engagement with the lever projection 16 and the valve 13 will close under the action of its spring 95 and the heat will be retained in the oven. 100

Removably secured on the upper side of the chamber 3 with suitable heat insulation to protect it from the heat of the oven is a clock-work time-alarm clock 19, the dial of which is graduated in minutes. The time alarm clock 19 is provided with an alarm 19*. This alarm clock is normally maintained stationary when the valve 13 is closed. It is released when the valve is opened, by 10 a light lever 20 pivotally mounted at 21 to some convenient part of the wall of the chamber 3. One end of this lever 20 is connected to the free end of the valve 13 and the other projects through an opening in 15 the wall of the chamber 3 and the casing of the alarm clock 19 to normally engage and hold against movement the balance wheel 22 or other suitable part of the clock mechanism.

20 When the valve 13 opens in the manner described under an increase of temperature beyond what it has been set for, the engagement of the end of the lever 20 with the clock mechanism is withdrawn, as shown by the 25 dot and dash lines in Fig. 2, and the clock is free to run.

The alarm being set for any desired number of minutes will ring that number of minutes after the predetermined temperature has been attained.

The thermometer control of the oven may be used without the time alarm, if found desirable.

Having now particularly described my invention, I hereby declare that what I claim as new and desire to be protected in by Letters Patent, is:

1. An oven temperature time alarm, comprising in combination, a heat indicator exposed to the heat of the oven, a clock adjustable to ring an alarm a predetermined time after release of its mechanism, means for normally holding the clock mechanism against movement, and means operative with 40 the heat indicator for releasing the clock mechanism when a predetermined heat is attained whereby the alarm may be given a predetermined time after the desired temperature is attained.

50 2. An oven temperature time alarm, comprising in combination, a heat indicator exposed to the heat of the oven, a clock mechanism adjustable to ring an alarm a predetermined time after release of its mechanism, 55 means for normally holding the clock mechanism against movement, and means operative with the heat indicator permitting escape of heated air from the oven when a predetermined heat is attained, and means co-60 operative therewith for releasing the clock mechanism.

3. An oven temperature time alarm, comprising in combination, a chamber having a

partition dividing it into two parts, one part of which is exposed to the heat of the oven 65 and the other part open to the atmosphere through a closable aperture, a heat indicator in that portion of the chamber which is exposed to the oven heat, a duct connecting the oven to that portion of the chamber which is exposed to the atmosphere, a valve normally closing that duct, means operative by movement of the thermal indicator for opening the valve and permitting escape of heated air from the oven when a predetermined 70 heat is attained, a clock mechanism adjustable to ring an alarm at any number of minutes after release of its mechanism, means normally arresting movement of the clock mechanism, and means operative by movement of the oven duct valve for releasing the clock mechanism.

4. An oven temperature time alarm, comprising in combination, a chamber having a partition dividing it into two parts, one part 85 of which is exposed to the heat of the oven and the other part open to the atmosphere through a closable aperture, a heat indicator in that portion of the chamber which is exposed to the oven heat, the dial of which indicator extends over that part of the chamber which is open to the atmosphere, a duct connecting the oven to that portion of the chamber which is exposed to the atmosphere, a valve normally closing that duct, a series 90 of levers pivotally mounted within that portion of the chamber which is exposed to the atmosphere, said levers projecting through apertures in the outer wall of the chamber and having portions projecting through the 95 dial of the heat indicator at angular distances apart corresponding to various temperatures, provision permitting said levers to be normally retained clear of the heat indicator pointer, and means for releasing said 100 levers to project that portion which projects through the dial into the path of the heat indicator, flexible means connecting each lever with the oven duct controlling valve, a clock mechanism adjustable to ring an 110 alarm at any definite time after release of its mechanism, means restraining movement of the clock mechanism, and means operated by the oven duct valve for releasing the 115 clock mechanism.

5. An oven temperature regulator comprising a chamber, a valved duct adapted for communication with the oven, a valve for said duct, a spring for closing said valve, a thermostat having a movable element and located in co-operative relation to said chamber, a valve opening lever connected with said valve and means whereby said lever may be engaged by said movable element at a predetermined temperature to open said 120 valve until the temperature falls again.

6. An oven temperature regulator comprising a chamber, a valved duct adapted for communication with the oven, a valve for said duct, a spring for closing said valve, 5 a thermostat having a movable element and located in co-operative relation to said chamber, a valve opening lever connected with said valve means whereby said lever may be engaged by said movable element at a pre-

determined temperature to open said valve 10 until the temperature falls again, and an alarm device, means co-operating with the valve for holding said alarm device inactive when said valve is closed and adapted to release said device when the valve is open. 15

In testimony whereof I affix my signature.

JOHN WM. SOUTHERN.
